UNITED STATES PATENT OFFICE.

OTTO A. SKIBBE AND BERT SALVAGE, OF CHICAGO, ILLINOIS, ASSIGNORS TO WILLIAM R. MANIERRE, OF CHICAGO, ILLINOIS.

CASTER RAISING AND LOWERING DEVICE.

1,129,429.

Specification of Letters Patent. Patented Feb. 23, 1915.

Application filed June 17, 1912. Serial No. 704,059.

To all whom it may concern:

Be it known that we, OTTO A. SKIBBE and BERT SALVAGE, citizens of the United States, and residing in Chicago, in the county of 5 Cook and State of Illinois, have invented certain new and useful Improvements in Caster Raising and Lowering Means, of which the following is a specification.

Our invention relates to attachments for 10 supporting tables, machine bases and the like, and has more particular reference to portable or movable apparatus of this character.

The primary object of our invention is to 15 provide an improved structure of this character, which will be simple, durable and reliable in construction, and effective and efficient in operation.

A further object of our invention is to 20 provide an improved attachment for a base or stand, more especially but not necessarily adapted for calculating machines and the like, whereby the base or stand may be used as a stationary structure but which may be 25 quickly and conveniently converted into a portable structure capable of being readily shifted about from place to place without disturbing the machine or apparatus supported thereby.

30 A further object of our invention is to provide improved mechanism which will restrict the movement of the base or stand to a definite path of travel or allow it to be shifted about indiscriminately.

35 The above and other new and useful objects hereinafter appearing are accomplished by, and our invention consists in the features of novelty in the construction, combination and arrangement of parts herein 40 described and shown in the accompanying drawings, which illustrate one embodiment of our invention, and more particularly set forth in the appended claim.

45 In the drawings: Figure 1 is a view in side elevation of an adding machine stand or base embodying our invention. Fig. 2 is a sectional view thereof on the line 2—2 of Fig. 1. Fig. 3 is an enlarged detail plan section on line 3—3 of Fig. 1. Fig. 4 is a 50 bottom plan view of one of the supporting casters or rollers illustrating the means for locking them in definite position.

55 Office machinery such as calculating, adding, billing, tabulating machines and the like are usually mounted on supports of

some character to elevate them into a position convenient for the operator. Supporting stands or bases are usually made especially for this class of machines for various obvious reasons, among which is to enable 60 the machine to be shifted about the office from place to place to place them in that position with relation to other office appliances, which is best adapted to expedite and facilitate the work of the operator. For 65 this reason it is customary to provide the stands with rollers, casters, wheels or other suitable supporting members which will enable the stands and their machines to be conveniently moved or shifted about with 70 the least physical exertion. The use of casters or such supporting members has been found to be a great source of annoyance and inconvenience to this extent; the operation of the machines by their usual operating levers tends to shift the machine stand around to varying positions, making the work of the operator difficult and tiresome and considerable time is lost in returning 75 the machine and stand to its proper position.

Our invention is intended to overcome these objections in a simple and efficient, yet satisfactory manner.

We have illustrated our invention as being embodied in a supporting stand or base A of a type which is intended more particularly for use with adding and calculating machines and the like, and while our invention is not restricted or limited to a stand structure of this kind, we have illustrated the invention in connection with this stand for the sake of clearness and in order that an understanding can be readily obtained of our invention. The stand illustrated is 85 generally rectangular in shape and is built up of a number of tubular members suitably fastened together to form a rigid structure. This stand has a vertical member A¹ at each corner and these verticals are connected by upper and lower horizontals or cross bars A² and A³ respectively, in such manner as to 90 form a rigid or solidly braced structure. The lower front horizontal or cross brace A⁴ extends from side to side of the stand and is set back from the front of the frame, as clearly shown in Figs. 1 and 2, for the 95 purpose of providing room for the operator's feet when the operator is manipulating the machine from a sitting position. 100 105 110

The lower ends A^5 of the verticals form legs or supports therefor, and constitute the points of contact with the floor upon which the stand rests. These supporting points 5 are preferably made in such form, for instance as shown in the drawings, that when the stand rests upon the floor, it cannot be easily moved, and to increase the frictional contact thereof with the floor, the lower 10 ends of the legs may be provided with some sort of non-sliding or frictional devices, if desired. In apparatus of this character it is extremely desirable that the stand be capable of being shifted about the office for various 15 obvious reasons but the weight of the machine and the stand prohibits the apparatus from being lifted or carried by the operator from place to place, and to drag the stand along the floor would scratch or mar the 20 floor or tear the carpet, as the case may be. Stands of this character have usually been provided with permanent casters or rollers on their legs to permit them being readily moved about, but the use of these permanent 25 attachments destroys the stability of the stand since the effort required to operate the machines is usually sufficient to move the stand and the work of the operator is rendered extremely tiresome and difficult.

30 Our invention enables the stand to be used either as a permanently fixed structure or as a portable structure, as desired, and we provide mechanism whereby the weight of the machine and stand may be quickly and 35 conveniently shifted or transferred either to supporting rollers or casters or to its permanent supports, as desired.

In the structure shown in the drawing, we have provided each leg or vertical, near 40 its lower end or point of contact A^5 , with a lever 1. These levers are pivoted near the lower ends A^5 of the verticals A^1 and each lever consists of a short and a long arm 2 and 3, respectively, and in order to provide 45 a convenient method of pivoting these levers upon the legs A^1 of the stand, we rigidly join the two arms 2 and 3 of each lever by means of a loop 4 of metal, preferably formed integral with the lever arms. These 50 loops, as clearly shown in Figs. 1, 2 and 3, embrace the legs A^1 of the stand and pivot bolts 5 are passed through the loops and legs (Fig. 3). The short arms 2 of the levers project preferably horizontally from 55 the legs and on their outer ends are provided with swiveled casters or roller members 6 of any suitable type best adapted to the particular requirements. The arms 3 of these 60 levers on corresponding sides of the frame rise angularly upward for a short distance and project horizontally toward each other. Their corresponding inner ends 7 are pivotally connected together, preferably by means of a slotted connection 8 (Figs. 1 65 and 2) so that the levers may be tilted or

swung about their pivotal points and still remain in connection at their inner ends 7. The levers, casters and the legs A^1 of the stand are all so proportioned and arranged with respect to each other that, as seen more 70 clearly in Fig. 1, by tilting the levers on their pivots, the casters may be brought into contact with the floor, or, in other words, lowered relatively to the ends A^5 of the stand legs A^1 . This results in elevating the 75 entire stand, raising the points of contact A^5 of the stand legs off of the floor and thereby transferring or shifting the weight of the machine and table to the rollers or casters 6. The stand may then be run 80 around the office to any place desired, and when that place is reached, the reverse operation of the levers will return the stand to its normal resting position with the lower ends A^5 of the legs upon the floor, or in 85 other words, the weight of the machine and stand may be retransferred to the lower ends of the legs A^1 . In order that this mechanism may be conveniently operated in unison we pivot a bail member 10 on two lower 90 side bars A^3 adjacent to and extending from side to side of the frame parallel with the lower cross bar A^4 as clearly seen in Figs. 1 and 2. From this bail, adjacent each side 95 of the frame, we extend the vertical links 11 to the pivotal points of connection between corresponding arms 3 of the levers 1. These links 11 are pivotally connected both to the bail member 10 and to the ends 7 of the lever arms 3, so that in effect a toggle 100 is formed at each side of the stand, the knuckle or knee of which is formed by the pivotal connection between the arms 3 of the levers 1. Hence, it will be seen that by 105 rotating the bail 10 about its pivotal points 11, the toggles may be operated through the medium of the links 11, thus swinging the levers 1 about their pivotal points and relatively raising or lowering the stand and casters, as the case may be. In order that 110 the bail may be conveniently operated by hand, we provide a rigid arm or lever 14 thereon adjacent one side of the stand. This lever 14 has a horizontally turned end 115 14¹ which rests upon the side bar A^3 , as clearly shown in Fig. 1, and which forms a 120 convenient operating handle. It is desirable, when the weight of the stand has been transferred to the casters, to lock the mechanism in such position. In order to accomplish this in a simple and effective manner, we so proportion the operating parts that the pivotal points 11¹ of the links 11 will 125 be carried slightly past the center lines X drawn between the pivotal points 12 of the bail and the pivotal points 8 of the operating levers 1, as clearly shown in Fig. 1. Thus, when the bail is rotated to elevate the stand and transfer the weight thereof to the casters, the turned end 14¹ of the arm 14 130

will allow the pivotal points 11¹ of the links to pass a slight distance beyond the center line X and thus effectually lock the mechanism in position and guard against the 5 accidental lowering of the stand while the stand is being shifted or transported from place to place. It is readily seen that the operating levers and other parts constitute a powerful system of multiplying levers 10 which enable the machine stand and machine thereon, even though of comparatively great weight, to be raised or lowered as the case may be by a slight amount of manual effort exerted on the operating 15 arm 14.

As previously mentioned we prefer to use swiveled casters 6, so that the machine may be indiscriminately moved about and readily turned as desired. It is oftentimes desirable, however, to move or transport the stand along a definite line of travel, say, in a straight line, and in order that this may be accomplished in a simple manner, we provide means by which the swiveling action 25 of the casters may be restricted or blocked. Referring more particularly to Figs. 1, 3 and 4, it will be seen that the outer ends of the arms 2 of the levers 1 may be provided with small substantially L-shaped members 30. These locking members 15 are preferably pivoted to the ends of the levers 2 and provided with some means, such as a frictional washer 15¹, for frictionally holding the members 15 in any position to which 35 they may be rotated. Thus, they may be swung down or rotated into a position so that the bend 15² in said members will engage the caster supports or yokes 6¹ and prevent or lock the casters against swiveling. These locking members, however, do not interfere with the free running of the casters themselves but merely prevent the 40 caster yokes from turning on the ends of the arms 2 of the operating levers. In this manner the frame may be caused to follow a definite straight line of travel. The horizontally extending portions 15³ of the locking members serve the purpose of forming

means by which the locking members may be conveniently actuated by the feet. We 50 usually provide short stop lugs 16 on the locking member which are intended to stop the rotation of the locking members in their proper locking position, as clearly shown in Fig. 4.

It will be obvious to one skilled in the art, after having obtained an understanding of our invention from the disclosures herein made, that our invention may be readily applied to or embodied in any suitable stand or structure wherein these requirements and conditions are to be met, all without departing from the spirit and scope of the invention. We do not desire to be understood, therefore, as being limited or restricted 65 to the particular structure shown in the drawing.

What we claim is:—

In a stand, the combination of a plurality of legs normally resting on the floor; a lever 70 pivoted to each leg and having a short arm and a long arm, the short arms of two of the levers being in alining relation with each other, and in parallel relations with the short arms of the other levers, the long 75 arms of the levers at one end of the stand being off-set toward the long arms of the levers at the other end of the stand, and the long arms of each of the levers being off-set upwardly; a caster at the free end of each 80 of the short arms of the levers; a manually operable lever pivotally mounted on the stand; and connecting links connecting the free ends of the long arms of the levers with said manually operable lever, the latter 85 when in one of its positions being adapted to cause the casters to support the stand.

In testimony whereof we have signed our names to this specification, in the presence of two subscribing witnesses, on this 15th day 90 of June A. D. 1912.
